UNITED STATES PATENT OFFICE

2,304,701

SWORD KNOT

Peter A. Merrigan, New York, N. Y.

Application August 21, 1941, Serial No. 407,831

6 Claims. (Cl. 41—10)

This invention relates to a sword knot of the type used by military officers and has for an object to provide a sword knot in which the slide and tassel carried by the strap are formed of metal plated with gold to simulate fabric material hitherto used in the construction of sword knots, but which now is almost unobtainable because of war conditions existing in parts of the world in which ordinarily the conventional sword knots are manufactured almost exclusively.

A further object is to provide a device of this character in which the component parts of the tassel and the slide may be formed of sheet metal stampings, for the most part.

A further object is to provide a device of this character which will be formed of a few strong, simple and durable parts, which will be inexpensive to manufacture, and which will not easily get out of order.

With the above and other objects in view, the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming a part of this specification:

Figure 1 is a side elevation of a military sword knot constructed in accordance with the invention.

Figure 2 is a longitudinal sectional view of the sword knot shown in Figure 1.

Figure 3 is a fragmentary longitudinal sectional view taken on the line 3—3 of Figure 2.

Figure 4 is a cross sectional view taken on the line 4—4 of Figure 2.

Figure 5 is a detail perspective view of one of the tubes forming the exterior of the tassel.

Figure 6 is a detail perspective view showing the tassel core with the two companion sections thereof separated to receive the strap between them.

Referring now to the drawing in which like characters of reference designate similar parts in the various views, 10 designates a strap, preferably formed of a looped length of material ornamented and colored to simulate gold. The strap may be formed of any suitable material. A slide 11 is mounted on the strap, and in carrying out the invention, this slide is formed of a flattened metal tube ornamented exteriorly and gold plated to simulate woven material as indicated at 12, see Figure 1.

The tassel carried by the strap comprises a core 13, see Figure 6, formed of two similar sections 14, spaced apart to receive the ends of the strap 10 between them, and having the external contour of a conventional tassel. The core may be formed of wood or other suitable inexpensive rigid material.

In further carrying out the invention, a plurality of tubes 15, one of which is shown in Figure 5, are disposed to extend side by side longitudinally of the surface of the core. The tubes are formed of sheet metal flattened and curved at the ends to form upper and lower hooks 16 and 17. The upper hooks open outwardly and the lower hooks open inwardly.

Circular tie wires 18 and 19 are engaged respectively through the upper hooks and through the lower hooks, see Figure 3, and secure the tubes to the core.

A flattened tubular sleeve 20 formed of metal, is disposed on the upper end of the core and extends to the upper hooks of the tubes. The tubular sleeve is formed, and plated on the exterior, to simulate gold woven material, as indicated at 21, see Figure 1. The sleeve coats with the tie wires 18 and 19 in holding the sections 14 of the core in clamping engagement with the end of the strap 10.

A frustum shaped collar 22 is mounted on the sleeve and extends over the upper hooks 16 of the tubes to conceal the hooks. The collar is formed of metal and is provided exteriorly with a spiral wound wire 23 embossed on the exterior to simulate twine, as shown at 24, see Figure 1.

A wad 25 is disposed on the bottom of the core and conceals the free ends of the lower hooks 17 of the tubes. The wad is preferably formed of yielding material such as felt or similar material.

In appearance the strap 10, slide 11, and tassel constructed as above described, closely simulates a conventional fabric material gold finished military knot, and in practice serves the same ornamental and useful purpose as the conventional fabric knot, although formed for the most part of sheet metal tubing gold plated.

From the above description it is thought that the construction and operation of the invention will be fully understood without further explanation.

50 What is claimed is:

1. In a military sword knot, the combination of a strap, a slide and a tassel on the strap comprising, a cord having a tassel contour, a plurality of tubes extending side by side longitudinally of the surface of the core flattened and curved

at the ends to form hooks, tie wires engaged through the hooks securing the tubes to the core, a flattened tubular sleeve on the upper end of the core extending to the upper hooks of the tubes, a frustum shaped collar on the sleeve concealing the upper hooks of the tubes, and a wad disposed on the bottom of the core concealing the bottom hooks of the tubes.

2. The structure as of claim 1 and in which said core is formed of two companion sections 10 clamping said strap between them.

3. The structure as of claim 1 and in which

said tubes are each formed of metal embossed spirally on the exterior to simulate tassel cords.

4. The structure as of claim 1 and in which said flattened sleeve is embossed on the exterior to simulate woven material.

5. The structure as of claim 1 and in which said collar is provided with an exteriorly disposed spirally wound wire embossed on the exterior to simulate binding twine.

6. The structure as of claim 1 and in which said wad is formed of yielding material.

PETER A. MERRIGAN.
